UNITED STATES PATENT OFFICE.

JAMES H. SMITH, OF PORT MURRY, NEW JERSEY.

AUTOMATIC SAFETY DEVICE FOR LOCOMOTIVES.

1,109,798.

Specification of Letters Patent. Patented Sept. 8, 1914.

Application filed May 2, 1913. Serial No. 765,167.

To all whom it may concern:

Be it known that I, JAMES H. SMITH, a citizen of the United States, residing at Port Murry, in the county of Warren and State of New Jersey, have invented a new and useful Automatic Safety Device for Locomotives; and I do hereby declare the following to be a full, clear, and exact description of the invention, such as will enable others skilled in the art to which it appertains to make and use the same.

This invention relates to a new and useful automatic safety device, particularly adapted for use upon locomotives and the like.

Heretofore, owing to the engineer not seeing the signal, or becoming unavoidably unconscious, thereby passing the signal, many accidents or mishaps and the like have occurred upon railroads.

Therefore, it is the aim of this invention to provide an efficient, practical and desirable automatic safety device, to eliminate or prevent such accidents.

To accomplish the prevention of the accidents, an apparatus including a partial rockable shaft, not only having connections with a steam controlling valve in the steam supply pipe, from the boiler to the chests of the locomotive, but also connections with the air controlling valve of the air brakes, whereby as an arm upon the rockable shaft comes in contact with a movable member of a signal apparatus, the shaft will be partially rotated, thereby closing or shutting off the steam and putting on the air brakes.

Another object of the invention is to provide means for equalizing the steam pressure upon opposite sides of the steam controller, thereby permitting the valve to be reset to an open position, owing to the fact that after the steam controlling valve becomes closed, the steam pressure above the valve is so great, that it would necessitate considerable manual strength to reset the valve.

A feature of the invention is the provision of means for holding the operating part out of operation, that is, upon a dead engine, while being drawn, so that the apparatus cannot be operated when passing a signal device.

In practical fields, it may be found necessary to subject the various details of construction to alterations, to which the pat-

entee is entitled, provided the alterations fall within the scope of what is claimed.

The invention comprises further features and combination of parts, as hereinafter set forth, shown in the drawings and claimed.

In the drawings:—Figure 1 is a view showing the application of the improved safety apparatus, as applied in the cab of a locomotive, showing the parts in their normal positions, prior to being actuated by a signal apparatus. Fig. 2 is a view similar to Fig. 1 showing the position of the parts after having been actuated. Fig. 3 is an enlarged side elevation of the steam controlling valve, showing the means for holding the valve open, and means for resetting the valve, and a by-pass pipe including a valve, whereby the steam pressure may be equalized upon opposite faces of the valve. Fig. 4 is a sectional view through the steam controlling valve. Fig. 5 is a view showing the operating parts of the apparatus held out of operation. Fig. 6 is a plan view of the means for actuating the air controlling valve. Fig. 7 is a side elevation of Fig. 6. Fig. 8 is a sectional view through a clutch for coupling the two sections of the partially rotatable shaft together. Fig. 9 is a plan view of the clutch, showing one of its members actuated, the same adapted to be actuated manually, so that one section of the partially rotatable shaft may be actuated independently of the other section, to prevent the apparatus from being operated. Fig. 10 is a view of the signal apparatus. Fig. 11 is a sectional view on line 11—11 of Fig. 10. Fig. 12 is a detail view of the spring tensioned section of the rotatable shaft.

Referring more especially to the drawings, 1 designates a locomotive, in the cab 2 of which, in any suitable location a steam controlling valve 3 is arranged, that is, in the steam supply pipe, between the boiler and the steam chest (not shown). This steam controlling valve may be either an angled valve or a straight line valve, but for convenience there is illustrated the angled valve. Also mounted in suitable bearings of the cab is a partially rotatable shaft 4, which comprises two sections 5 and 6. The section 5 is provided with a coil spring, one end of which spring 7 is connected at 8 to a portion of the cab, while the other end of the spring

is connected at 9 to the section 5 of the shaft, whereby as the section 5 is rotated partially in one direction, the spring will tend to instantly return the section of the shaft to its normal position. The section 5 of the shaft 5 is provided with an offset lug 10, to which one end of the link 11 is connected, which in turn is pivotally connected to a slide 12. This slide 12 is mounted in suitable guides 13 of an upwardly extending portion 14 of the top 15 of the steam controlling valve casing. The valve 16 proper is mounted upon the stem 17, and is adapted to coöperate with the valve seat 18. A spring 19 is 10 interposed between the valve proper 16 and a shoulder of the casing, so that when the valve stem is released, the valve 16 proper will close, by the action of the spring 19. Mounted upon the valve stem and secured 15 thereto by a pin, is a collar 20, under which the slide 12 engages, for normally holding the valve stem in its uppermost position, with the valve 16 proper normally opened, so that when the locomotive is under way, 20 the steam from the boiler will pass uninterrupted to the steam chest (not shown), thereby keeping them supplied. The upper end of the valve stem is mounted in the bracket arm 21, rising from the top 15 of 25 the valve casing. When the section 5 of the partially rotatable shaft is actuated in order to withdraw the slide 12 from under the collar 20, the valve proper 16 will close automatically to the action of the spring 19. It 30 will be understood that after the valve 16 has closed, the steam pressure above the valve 16 is so great, that it is hardly possible to manually unseat the valve. To overcome this excessive steam pressure upon the top 35 of the valve 16 a by-pass pipe 22 enters the supply pipe above the valve 16, as at 23, and connects to the valve casing 3 below the valve 16, as at 24. This by-pass pipe 22 is provided with a valve 25, whereby upon 40 opening the same, the steam above the valve 16 may be allowed to pass into the valve casing 3 below the valve 16, thereby equalizing the pressure upon opposite sides of the valve. After equalizing the steam pressure 45 in such a manner, the valve 16 may then be manually raised from its seat, so that the collar 20 upon the valve stem will be engaged by the slide 12. Rising from the top 50 15 of the valve casing is a bifurcated arm 26, while 27 denotes a lever having a slot 28, through which a bolt 29 of the bifurcated arm extends, thereby mounting the lever 27 in the arm. One end of the lever is provided 55 with an enlarged portion 30 adapted to engage under the collar 20 of the valve stem, whereby the valve stem including the valve 16 may be raised, in order to be reset. When 60 using the lever 27 for resetting the valve stem and its valve, the lever 27 is arranged, 65 so that the bolt 29 engages the offset por-

tion 31 of the slot 28, in order to hold the lever true to its work.

Projecting laterally from the section 5 of the partially rotatable shaft is an arm 32, to which a link 33 is pivotally connected. The link 33 is in turn pivoted at 34 to the slide bar 35, which is mounted in a bifurcated guide 36 of the standard 37. Extending vertically through the end 38 of the slide bar is a rod 39, the upper end of which is guided in a bifurcation 40 of a pivoted bracket 41, which is pivoted at 42 to the slide bar 35. Interposed between the end 38 of the slide bar 35 and a nut 43 upon the rod 39 is a coil spring 44, which holds the nut 43 in contact with the under face of the lateral portion 45 of the pivoted bracket. The lateral portion 45 of the pivoted bracket is provided with downwardly extending lugs 46 to engage the nut 43, so as to hold the bracket in place. The lower end of the rod 39 engages a bifurcation 47 of the arm 48 of the stem 49 of the valve 50, which is located in the air pipe 51 of a usual air brake system (not shown). When the section 5 of the partially rotatable shaft is partially rotated, the slide bar 35 is reciprocated, through its connection to the arm 32 of the section 5 of the shaft, and which slide bar 35 in turn actuates the arm 48, which in turn actuates the valve 50 to its fullest possible extent, so as to apply the emergency brakes instantly, and then subsequently upon reverse movement of the section 5 of the shaft, the bar 35 is partially returned, which in turn partially returns the valve 50 to the ordinary service position, thereby holding the brakes applied in the ordinary normal manner. At the same time the air brakes are applied, the steam is also instantly cut off. Then after the train has stopped, the valve 25 of the by-pass pipe is actuated, so as to equalize the steam pressure above and below the valve 16. The valve 16 may then be raised to an open position, and supported owing to the slide 12 engaging under the collar 20. When the slide again engages under the collar 20, the section 5 of the partially rotatable shaft returns to its normal position, the arm 32 returning the slide bar 35, which then actuates the valve 50 from the ordinary train line to a closed position, which is the normal condition of the valve 50, prior to the brakes being applied. However, when the bar 35 is actuated to apply the emergency brake, and after which the section 5 of the partially rotatable shaft is in the act of returning to its normal position, the slide 12 engages the side of the collar 20, thereby preventing the section 5 of the shaft from returning to its full normal position, as well as holding the slide bar 35 against its returning to its full normal position, thereby holding the valve 50 to the ordinary train line connection, with

the air brake applied in the usual manner. Extending laterally from the section 5 of the shaft is an arm 51. By the pressing of the rod 39 downwardly, the pivoted bracket 41 may be swung upon its pivot, so that the lateral portion 45 will be disengaged from the nut 43, and by action of the spring 44, the rod 39 will move upwardly, thereby disengaging from the bifurcation of the arm 48, so that the valve 50 cannot be operated. When the rod 39 moves upwardly, it is limited in its movement by the pin 52. In this manner the valve 50 cannot be operated. To prevent the valve 16 from being operated, a hook 53 is connected to the arm 51, thereby holding the section 5 of the shaft actuated, with the slide 12 from beneath the collar 20. When the section 5 of the partially rotatable shaft is held in such wise, a hook 54 pivoted to the valve casing 3 is connected to the lever 27, thereby holding the enlarged portion 30 of the lever 27 under the collar 20, in order to hold the valve 16 normally unseated, and which cannot be released by the actuation of the section 5 of the shaft, owing to the fact that the slide 12 is held withdrawn from beneath the collar 20.

Mounted upon the shaft 4 is a two part clutch device 58, comprising the parts 59 and 60. The part 59 is fixed to the section 5 of the shaft 4 by the pin 61, while the part 60 is keyed to the section 6 of the shaft 4 by the pin 62. This pin 62 extends into the longitudinally extending key-way 63, thereby holding the part 60 so as to rotate with the section 6 of the shaft when the shaft is rotated in one direction, say for instance, in the direction of the arrow *a*. The part 59 of the clutch device, holds the sections 5 and 6 of the shaft 4 axially in alinement. When the arm 64 of the section 6 of the shaft comes in contact with an obstruction, say for instance, a signal apparatus 65, the section 6 is rotated in the direction of the arrow *a*, and by reason of the fact that the part 60 is keyed to the section 6 of the shaft, the clutch portions 66 and 67 of the said parts 59 and 60 will coöperate, thereby causing the two sections of the shaft 4 to rotate as one body. The arm 64 contacts with the signal apparatus, in case the engineer does not observe the danger signal, or is unavoidably unconscious, in which case the two sections 55 of the shaft are rotated as one body, thereby cutting off the steam and throwing on the brakes, to emergency and then returning them to service positions. However, when a train is approaching the signal and it is set 60 at danger, and the engineer observes the same, it is his purpose to stop the train, but not operate the safety device. To accomplish this, the part 60 of the clutch device is reciprocated in the direction of the arrow *b*, 65 by means of the lever 67 sufficiently to dis-

connect the clutch parts 59 and 60, then only the section 6 of the shaft is rotated in the direction of the arrow *a*, by the arm 64 contacting with the signal. When only the section 6 of the shaft is rotated, the key or pin 62 enters the transverse key-way 68, and after the arm 64 has passed the signal apparatus, the section 6 of the shaft is returned to its normal position by the spring 70, one end of which is connected to the cab construction, while the other end is connected to the section 6 as at 71 of the shaft. The lever 67 is connected to the part 60 in the usual manner, as shown at 72. When the engine is so positioned that the arm 64 is 75 upon the other side of the signal apparatus, opposite to the side toward which the train or engine approaches, and it is the desire of the engineer to back, the arm 64 will contact with the signal apparatus, thus operating 80 the section 6 of the shaft in the direction of the arrow *a*. When such is the case, the inclined portions 73 and 74 of the parts 59 and 60 coöperate in such wise as to separate the clutch portions 66 and 67, thereby not 85 operating the safety device. Also when such operation takes place, the spring 75 (one end of which is connected at 76 to a portion of the cab, while the other end is connected at 77 to the part 60 of the clutch device) is 90 placed under torsional tension, and after the arm 64 has passed the signal apparatus subsequently to rotating the section 6 in the direction of the arrow *a*, the torsional action of the spring 75 will return the section 100 6 to its normal position, with the part 60 in clutch with the part 59. When the train is approaching the signal which is set at danger, and the engineer does not desire to operate the safety apparatus, he manipulates 105 the lever 67, in the manner hereinbefore stated, and when so manipulated, so as to separate the parts 59 and 60, the dog 79 engaging the teeth of the rack 80, holds the lever 67 actuated. The dog 79 after the arm 110 64 has passed the signal apparatus may be actuated by the hand grip 81, to release the lever 67.

The signal apparatus 65 comprises the usual standard 82, having the usual semaphore blades 83 and 84. A rod 85 is connected to the blade 84, and in turn to the lever 86 pivoted at 87. The lever 86 moves in a guide 88 of the arm 89. On each side of the arm is a bracket 90, in which and also in the arm a pin 91 is mounted and guided. These pins 91 are provided with integral collars 92, between which and the brackets 93 are interposed, thereby holding the pins against the lever 86. When the arm 64 contacts with either side of the lever 86, the lever pushes against one or the other of the pins 91, sufficiently to allow the lever 86 to enter either one of the notches 97 of the arms 89, thereby preventing the lever 86 130

from instantly oscillating upon its pivot. This signal apparatus is operated in the usual manner by any conventional form of electrical block system, so that just so soon 5 after the arm 64 passes the lever 86, and the engine enters the next block, one or the other of the pins 91 will push the lever 86 out of one or the other of the notches 97, and then through the medium of electrical 10 block system (not shown), will actuate the lever 86 and throw the signal blades to caution.

From the foregoing it will be noted, there 15 has been devised an exceedingly efficient safety apparatus, particularly applicable to locomotives, for applying the brakes automatically and shutting off the steam instantly, and one which has been found exceedingly desirable and practical.

20 The invention having been set forth, what is claimed as new and useful is:—

1. In combination with a locomotive, a partially rockable shaft comprising two sections having coupled connections, one of 25 said sections having a device to contact with a member in its path to actuate one section which in turn operates the other section, means operated by said shaft for actuating the controlling mechanism of the locomotive, 30 means upon said shaft for returning the same to a partial normal position, thereby returning the air valve of the controlling

mechanism from emergency to service position, and means in the path of the first means for limiting the return of said shaft to a partial normal position.

2. In combination with a locomotive, a partially rockable shaft comprising two sections having coupling connections, one of the sections having a device to contact with a member in its path to actuate said section which in turn operates the other section, means operated by said shaft for actuating the controlling mechanism of the locomotive, means upon said shaft for returning the same to a partial normal position, thereby returning the air valve of said controlling mechanism from emergency to service position, means in the path of the first means for limiting the return of said shaft to a partial normal position, means for holding the first means against operation, parts of said first means adapted to be disconnected from the air valve, and means for operating the coupling connections whereby the section of said shaft having the device may operate idly.

In testimony whereof I have signed my name to this specification in the presence of two subscribing witnesses.

JAMES H. SMITH.
